D10-7.

OR D 14,532

EX

No. 14,532

JAN 1, 1884

UNITED STATES PATENT OFFICE.

JOHN BARCLAY McCARTY, OF NEW YORK, N. Y.

DESIGN FOR A CLOCK-CASE.

SPECIFICATION forming part of Design No. 14,532, dated January 1, 1884.

Application filed October 17, 1883. Term of patent 3½ years.

To all whom it may concern:

Be it known that I, J. BARCLAY McCARTY, of the city, county, and State of New York, have invented and produced a new and original Design for a Heraldic Clock-Case, of which the following is specification.

Reference is to be had to the accompanying photograph, forming part of this specification, which shows a face view of my newly-designed clock-case.

My newly-designed clock-case is made to represent a heraldic eagle, A, on the breast of which a shield, B, is held diagonally, on which shield the numerals from one to twelve are produced in a circle, and which shield can also be ornamented by means of circular ornaments within the circle of numerals. The shield B is of a contrasting shade of color

from the eagle. The heraldic eagle A is produced upon a larger shield, C, which forms a background for the eagle.

I claim—

1. The herein-described design for a clock-case, consisting of a heraldic eagle, on the breast of which is a diagonal shield carrying the clock-dial, the shield and eagle being of contrasting shades of color, as set forth.

2. The herein-described new design for clock-cases, consisting of a heraldic eagle, on the breast of which a shield carrying the clock-dial numerals is placed, which heraldic eagle is secured on a shield, as set forth.

JOHN BARCLAY McCARTY.
